LAPPING ARM

Herbert S. Indge, Westboro, Mass., assignor to
 Norton Company, Worcester, Mass., a corpora-
 tion of Massachusetts

Application March 17, 1941, Serial No. 383,755

8 Claims. (Cl. 51—67)

The invention relates to lapping machines, and more particularly to an improved crankpin lapping apparatus.

One object of the invention is to provide a simple and thoroughly practical crankshaft lapping machine. Another object of the invention is to provide an improved lapping arm. Another object of the invention is to provide a lapping arm having a yieldably mounted, reciprocably driven lapping element. Another object of the invention is to provide a lapping arm having work engaging shoes to engage the periphery of the work to be lapped which serve as a guide for the lapping arm, and to provide the arm with a yieldably mounted reciprocable lapping element. A further object of the invention is to provide an improved lapping arm construction which may be applied as an attachment to a machine such as, for example, that shown in my prior U. S. Patent No. 2,166,009 dated July 11, 1939. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing in which is shown one of various possible embodiments of the mechanical features of this invention,

Fig. 1 is a fragmentary side elevation of the improved lapping arm together with the supporting and driving mechanism therefor;

Fig. 2 is a fragmentary sectional view, on an enlarged scale, taken approximately on the line 2—2 of Fig. 1; and

Fig. 3 is a vertical sectional view, taken approximately on the line 3—3 of Fig. 2, showing the mechanism for reciprocating the lapping element.

A crankshaft lapping machine of the type shown in my prior Patent No. 2,166,009 is provided with a pair of parallel lapping arm supporting rods or slides 10 and 11 which serve as supports for a plurality of lapping arm supporting members 12. The supporting member 12 is provided with a lower half 13 by means of which the supporting member 12 may be readily clamped in adjusted position on the rods 10 and 11 with a lapping element to be hereinafter described in alignment with the work piece to be lapped. The lapping arm supporting member 12 serves as a support for a pivotally mounted arm 14. A pivotal connection 15 is provided between

the supporting member 12 and the pivotally mounted arm 14. A lapping arm 16 is pivotally connected by a pivotal connection 17 to the upper end of the arm 14.

5 The lapping arm 16 comprises a pair of parallel side plates which are spaced apart by spacing blocks 18, 19 and 20 at one end and by a bracket 21 which is formed as an integral extension of a fluid pressure cylinder 22. The lapping arm 16 serves as a support for a pair of pivotally mounted members 23 and 24 which are pivotally connected by studs 25 and 26, respectively, with the lapping arm 16. The arm 23 is provided with a pair of work engaging shoes 27 and 28 which are arranged to engage the upper portion of a work piece 29. The lower arm 24 is provided with a work engaging shoe 30 which is arranged to engage the under side of the work piece 29. A pair of toggle levers 31 and 32 are connected at their opposite ends by studs 33 and 34, respectively, with the members 23 and 24, respectively. The inner ends of the toggle levers 31 and 32 are connected by a common stud 35 which slides within elongated slots 36 formed in the opposite side plates of the lapping arm 16.

A fluid pressure mechanism is provided to actuate the toggle levers 31 and 32 so as to swing the pivotally mounted members 23 and 24 to position the work shoes 27, 28 and 30 either in an operative position in engagement with the periphery of the work piece 29 (Fig. 1) or in an inoperative position out of engagement with the work after a lapping operation has been completed. The hydraulic cylinder 22 contains a 35 slidably mounted piston 36 which is connected to one end of a piston rod 37. The piston rod 37 is connected by a stud 38 to the upper end of a connecting rod or link 39, the lower end of which is connected with the stud 35. In the position of the parts as shown in Fig. 1, fluid under pressure is admitted from a source of supply, such as a fluid pump (not shown) within the base of the crankshaft lapping machine, through the pipe 40 and a passage 41, into a cylinder chamber 42, to cause the piston 36 to move upwardly toward the right to the position shown in Fig. 1. During this movement fluid is exhausted from a cylinder chamber 43 above the piston 36 through a pipe 44 into a reservoir (not shown).

40 After a lapping operation has been completed and it is desired to remove the work engaging shoes 27, 28 and 30 from operative engagement with the work piece 29, the direction of movement of fluid under pressure is reversed and fluid under pressure is passed through the pipe

44 into the cylinder chamber 43 to cause a downward movement of the piston 36 which transmits a downward movement toward the left through the piston rod 37, connecting rod or link 38, to move the stud 35 downwardly within the elongated slots 36, which movement serves to break the toggle levers 31 and 32 so as to rock the arms or members 23 and 24 to swing the work engaging shoes 27, 28 and 30 to an inoperative position out of engagement with the work piece 29.

The work engaging shoes 27, 28 and 30, when in an operative position in engagement with the periphery of a crankpin 29, serve as a support and guide to move the lapping arm 16 as the crankpin 29 is revolved. A pair of spaced guide plates 45 are fixedly mounted on the lapping arm supporting member 12 to serve as a guide for the lapping arm 16 during its swinging movement.

In order to attain one object of the invention, the lapping arm 16 is provided with a reciprocable lapping element comprising a lapping stick 50 of bonded abrasive material which is arranged to be reciprocated at a comparatively rapid rate while maintained in yielding engagement with the periphery of the work piece to be lapped.

The swinging arm 23 is provided with an upwardly extending portion 51 which is provided with a plurality of elongated slots 52, 53, 54 and 55 which serve to support a pair of spaced parallel yieldable elements, such as relatively thin flat springs 56 and 57. The thickness of the springs 56 and 57 has been somewhat exaggerated in the drawing in order to clarify the illustration. A pair of plates 58 and 59 are provided adjacent to the upper ends of the springs 56 and 57. A plurality of studs 60, 61, 62 and 63 loosely fit within the elongated slots 52, 53, 54 and 55, respectively. The studs 60, 61, 62 and 63 are provided with threaded end portions 64 and 65. The threaded portions 64 and 65 of the studs pass through holes formed in the springs 56 and 57, respectively, and pass through corresponding holes in the plates 58 and 59. Clamping nuts 66 and 67 are provided to clamp the plates 58 and 59 and the springs 56 and 57, respectively, into fixed relation with the studs 60, 61, 62 and 63. The length of the body of the studs 60, 61, 62 and 63 is slightly greater than the thickness of the member 51 so that due to the elongated slots 52, 53, 54 and 55, the springs 56 and 57 are free to slide in a substantially vertical direction. The lower end of the springs 56 and 57 are fastened to a block 68 by means of screws 69 and 70. The block 68 serves as a support for a lapping stick holder 71 which supports the lapping stick 50.

The flat supporting springs 56 and 57 are relatively thin so that the lapping stick 50 may be reciprocated in operative contact with the peripheral surface of the crankpin 29 to be ground. A crank motion is provided for oscillating or reciprocating the stick 50 which may comprise a rock shaft 75 journalled within the arm 23. The rock shaft 75 supports a downwardly extending arm 76 having a rounded end 77 which engages a hole 78 formed in the block 68 (Fig. 3). A rock arm 79 is mounted on the other end of the rock shaft 75. The upper end of the arm 79 is provided with a vertically extending groove 80 within which a crankpin 81 rides. The crankpin 81 is eccentrically mounted on a rotatable plate 82 formed on the lower end of a rotatable shaft 83. The upper end of the shaft 83 carries a gear 84 which meshes with a gear 85. The

gear 85 is mounted on a rotatable shaft 86. It will be readily apparent from the foregoing disclosure that rotation of the shaft 86 will be transmitted through the gear 85, the gear 84, the shaft 83, to revolve the crankpin 81 (Fig. 3) which in turn will oscillate the rock arm 79, the rock shaft 75, and the rock arm 76 to oscillate or reciprocate the lapping stick 50 so that it abrades or laps the entire length of the peripheral surface of the crankpin 29 as it is rotated.

It is desirable that the lapping stick 50 be maintained in yielding engagement with the work piece 29 so that a uniform engagement of the lapping stick 50 may be had during its entire reciprocatory stroke. In order to accomplish this desired result, a pair of compression springs 87 and 88 are interposed between the member 51 and the block 68. Due to the fact that the springs 56 and 57 together with the entire lap element assembly are free to move in a vertical direction, the compression springs 87 and 88 will maintain the lapping stick 50 in yielding engagement with the periphery of the crankpin 29 during the lapping operation.

A suitable driving mechanism is provided whereby a plurality of lapping arms may be utilized and a plurality of lapping sticks 50 supported thereby may be readily driven. A pair of spaced brackets 90, only one of which has been shown in the drawing, serve as a support for a rotatable shaft 91 which is driven by means of an electric motor 92. Each of the lapping arm supporting members 12 is provided with an upwardly extending bracket 93 each of which contains a spiral gear 94 which is slidably keyed to the shaft 91 so as to facilitate a longitudinal adjustment of the lapping arm supporting member 12 in setting up the machine. Each of the spiral gears 94 meshes with a spiral gear 95 which is rotatably supported within the bracket 93 and is drivingly connected by means of a flexible driving shaft 96 with the shaft 86 on the lapping arm 16. It will be readily apparent from the foregoing disclosure that rotation of the shaft 91 by the motor 92 will be transmitted through the spiral gear 94, the spiral gear 95, the flexible driving shaft 96, to rotate the shaft 86 and thus transmit a reciprocatory movement to the lapping stick 50. Due to the flexible driving shaft 96, the lapping arm 16 may readily swing in a desired path as the crankpin 29 revolves during a lapping operation.

It will be readily apparent from the foregoing disclosure that one or more of the improved lapping arms 16 may be mounted on a crankshaft lapping machine of the type shown in my prior U. S. Patent No. 2,166,009. The driving mechanism including the shaft 91 and electric motor 92 together with the spaced supporting brackets 90 may be readily supported on the pivotally mounted lap supporting arms 80 so that the entire lapping arm assembly may be readily rocked to an inoperative position during the loading operation.

The operation of the improved lapping arm will be readily apparent from the foregoing disclosure. Assuming the parts to have been previously adjusted, when it is desired to start a lapping operation fluid under pressure is admitted through the pipe 40, to the cylinder chamber 42, to move the piston 36 into the position illustrated in Fig. 1, which movement shifts the toggle levers 31 and 32 into the straight line position to swing the work engaging shoes 27, 28 and 30 into operative engagement with the work

piece 29. At the same time, the electric motor 92 is started which, in a manner hereinabove described, serves through the flexible driving shaft 96 to impart a rapid reciprocatory movement to one or more of the lapping sticks 50, depending upon the number of lapping arms 16 mounted upon the machine.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In a lapping machine having a movable lapping arm, a work engaging shoe on said arm to engage the periphery of a work piece so as to take up the thrust of said arm, a reciprocable lapping stick on said arm adjacent to said shoe, a flat spring on said arm which is free to move in a direction normal to the work axis to support said lapping stick, and means to flex said spring so as to impart a reciprocatory movement to said lapping stick.

2. In a lapping machine having a pivotally mounted lapping arm, a work engaging shoe on said arm to engage the periphery of a work piece so as to support and steady one end of said arm, a reciprocable lapping stick on said arm adjacent to said shoe, a flat spring on said arm which is arranged to move in a direction normal to the work axis to support said lapping stick, yieldable means to maintain said lapping stick in yielding engagement with a work piece, and means to flex said spring so as to impart a reciprocatory movement to said lapping stick.

3. In a crank lapping machine having a pivotally mounted lapping arm, a pair of toggle levers mounted on said arm, means to actuate said toggle levers, opposed work engaging shoes each one connected to one of said levers, a reciprocable lapping stick, a flat spring connected with one of said levers yieldably to support said lapping stick in operative engagement with the periphery of a work piece, and means including an oscillatable lever to flex said spring so as to impart a reciprocatory movement to said lapping stick.

4. In a crank lapping machine having a pivotally mounted lapping arm, a pair of toggle levers mounted on said arm, means to actuate said toggle levers, opposed work engaging shoes each connected to one of said levers, a reciprocable lapping stick, a pair of spaced flat parallel springs connected with one of said levers yieldably to support said lapping stick in operative engagement with the periphery of a work piece, and means including an oscillatable lever to flex said spring so as to impart a reciprocatory movement to said lapping stick.

5. In a crank lapping machine having a pivotally mounted lapping arm, a pair of toggle levers

6
vers mounted on said arm, means to actuate said toggle levers, opposed work steadyng shoes each connected to one of said levers so as to take up the thrust of said arm, a reciprocable lapping stick, a flat spring on one of said levers which is free to move in a direction normal to the work axis to support said lapping stick, yieldable means to maintain said lapping stick in yielding engagement with a work piece, and means including a positively rotated crank operatively connected to flex said spring so as to impart a reciprocatory movement to said lapping stick.

6. In a crank lapping machine having a support for a rotatable work piece, a pivotally mounted lapping arm, a pair of toggle levers mounted on said arm, means to actuate said toggle levers, opposed work steadyng shoes, each shoe connected to one of said levers so as to support and steady one end of said arm relative to the work piece, a reciprocable lapping stick, a pair of flat parallel spaced springs on one of said levers which are free to move in a direction normal to the work axis to support said lapping stick, yieldable means to maintain said lapping stick in yielding engagement with a work piece, and means including a positively rotated crank operatively connected to flex said springs so as to impart a reciprocatory movement to said lapping stick.

7. In a crank lapping machine having a support for a rotatable work piece, a pivotally mounted lapping arm, a pair of toggle levers mounted on said arm, means to actuate said toggle levers, opposed work engaging shoes each connected to one of said levers so as to support and steady one end of said arm relative to the work piece, a reciprocable lapping stick, a pair of flat parallel spaced springs on one of said levers which are free to move in a direction normal to the work axis to support said lapping stick, means including a crankpin operatively connected to flex said springs so as to impart a reciprocatory movement to said lapping stick, and a flexible driving shaft operatively connected to rotate said crankpin, whereby a reciprocatory motion may be transmitted to the lapping stick during the swinging movement of the lapping arm.

8. In a crank lapping machine having a pivotally mounted lapping arm, a pair of toggle levers mounted on said arm, means to actuate said toggle levers, opposed work engaging shoes each connected to one of said levers, a reciprocable lapping stick, a pair of flat parallel spaced springs which are free to move in a direction normal to the work axis to support said lapping stick, means including a crankpin operatively connected to flex said springs, a motor driven shaft on said machine, and a flexible driving shaft operatively connected between said motor driven shaft and said crankpin whereby rotation of said shaft serves to revolve said crankpin so as to flex said springs and thereby impart a reciprocatory motion to the lapping stick.

HERBERT S. INDGE.
